UNITED STATES PATENT OFFICE.

ROBERT R. BREN, OF NEW YORK, N. Y.

DESIGN FOR A SASH-WEIGHT.

SPECIFICATION forming part of Design No. 26,174, dated October 13, 1896.

Application filed September 4, 1896. Serial No. 604,906. Term of patent 7 years.

To all whom it may concern:

Be it known that I, ROBERT R. BREN, of New York city, in the county and State of New York, have invented and produced a new and original Design for a Sash-Weight, of which the following is a full, clear, and exact description.

Reference is to be had to the accompanying drawings, forming a part of this specification, in which similar characters of reference indicate corresponding parts in all the figures.

Figure 1 is an elevation, partly in vertical section, of a sash-weight embodying my new design. Fig. 2 is a broken side elevation. Fig. 3 is a view similar to Fig. 2, but taken from the opposite side of the sash-weight; and Fig. 4 is a top view.

The design in its entirety includes the elongated body *a*, having at one side inward from the end a recess *b*, the bottom and top walls *b'* *b''* of which flare, as seen clearly in Figs. 1 and 2, and a recess *c* at the opposite side, said recess *c* extending through the end or top of the weight, the two recesses communicating by an orifice *d*, which appears above the center of the recess *b*. The side walls *c' c''* of the recess *c* flare outwardly, as seen best in Figs. 3 and 4, the bottom wall *c''* curves downwardly and outwardly from the orifice *d* to the mouth

of recess *c*, and the back wall *c³* is approximately vertical and is back of the inner end of the flaring bottom wall *b'* of recess *b*; that is, the said bottom wall extends inward beyond the line of the vertical wall *c³*. Further, the flaring bottom wall *b'* and the flaring bottom wall *c²* of the opposite recess form a vertically-ranging projection *e* at one side of the axial center of the weight, and the sides of the said projection are at an acute angle.

The leading feature of my design consists in the sash-weight having a recess at one side inward from the end, a recess at the opposite side extending through the end of the weight, and an orifice establishing communication between the two recesses, the bottom wall of the first-mentioned recess extending inward and upward from the mouth to a point beyond the back wall of the opposite recess, and the said orifice appearing above the center of the said first-mentioned recess.

I claim—

The design for a sash-weight as herein shown and described.

ROBERT R. BREN.
